[57] CLAIM

The ornamental design for a combined coffee table and dual foot rail unit, substantially as shown and described.

DESCRIPTION

FIG. 1 is a side elevational view of a combined coffee table and dual foot rail unit showing my design;

FIG. 2 is a top plan view;

FIG. 3 is an end view; and

FIG. 4 is a bottom plan view thereof.

The side and end view of the combined coffee table and dual foot rail unit not shown are mirror images of the side and end shown in FIGS. 1 and 3 respectively.

FIG. 1

FIG. 2

FIG. 3

FIG. 4
